The ornamental design for a light emitting diode, as shown and described.

DESCRIPTION

FIG. 1 is a front top side perspective view of a light emitting diode in accordance with my new design;

FIG. 2 is a front elevational view of the light emitting diode in accordance with my new design;

FIG. 3 is a rear elevational view of the light emitting diode in accordance with my new design;

FIG. 4 is a right side end elevational view of the light emitting diode in accordance with my new design;

FIG. 5 is a left side end elevational view of the light emitting diode in accordance with my new design;

FIG. 6 is a top plan view of the light emitting diode in accordance with my new design;

FIG. 7 is a bottom plan view of the light emitting diode in accordance with my new design; and,

FIG. 8 is a vertical center cross sectional view of the light emitting diode in accordance with my new design taken along a left to right direction thereof.

The opaque line shading illustrates a translucent portion of the light emitting diode.

The cross sectional view illustrated in FIG. 8 is presented solely for the purpose of clarifying the shape of exterior surface of the claimed design.
